(57) **CLAIM**

The ornamental design for a speaker storage bag, as shown and described.

DESCRIPTION

FIG. 1 is a top perspective view of a speaker storage bag, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view showing the speaker storage bag in a use state;

FIG. 10 is an enlarged detail view of area 10 in FIG. 1;

FIG. 11 is an enlarged detail view of area 11 in FIG. 1; and,

FIG. 12 is an enlarged detail view of area 12 in FIG. 1.

The broken lines in the drawings illustrate the portions of the speaker storage bag, which form no part of the claimed design.

The dash-dot-dash broken lines encircling the enlarged views are for annotative purposes only and form no part of the claim thereof.

1 Claim, 12 Drawing Sheets
